UNITED STATES PATENT OFFICE.

JAMES G. BARRETT, OF WILLIAMSTOWN, MASSACHUSETTS.

RAIL-HOLDING MEANS.

No. 820,085.

Specification of Letters Patent.

Patented May 8, 1906.

Application filed October 31, 1905. Serial No. 285,288.

To all whom it may concern:

Be it known that I, JAMES G. BARRETT, a citizen of the United States, residing at Williamstown, in the county of Berkshire and State of Massachusetts, have invented a new and useful Rail-Holding Means, of which the following is a specification.

This invention relates to means for holding railroad-rails from creeping or, in other words, from moving longitudinally.

The principal object is to provide novel means of a simple nature which can readily be applied to the rail, be securely associated with the adjacent ties, and consequently anchored in the ballast, and will efficiently lock the rail against movement in either direction without altering or injuring said rail.

A further object is to provide a structure that will be very durable and is not liable to derangement or injury from exposure to the elements and to the jars and vibrations incident to the track held thereby.

An embodiment of the invention that is at present considered the preferable one is illustrated in the accompanying drawings; but an inspection of the claims will clearly show that said invention is not limited solely to the embodiment disclosed.

In the drawings, Figure 1 is a side elevation of a portion of a track with the holding means applied to the rail thereof. Fig. 2 is a cross-sectional view through the same. Fig. 3 is a longitudinal sectional view taken on the line 3 3 of Fig. 2. Fig. 4 is a horizontal sectional view taken on the line 4 4 of Fig. 2. Fig. 5 is a bottom perspective view of the holding-plate and the associated portions of the jaws. Fig. 6 is a perspective view of one of the rail-engaging cam elements.

Similar reference-numerals designate corresponding parts in all the figures of the drawings.

In the structure illustrated two adjacent ties 7 are shown, upon which is located the ordinary railroad-rail 8. Fitted between the ties and beneath the rail is an anchor-block 9, that may be of any suitable material, said block thus being held securely in the ballast. Embracing the anchor-block are jaws 10, having their upper ends enlarged, as shown at 11, said upper ends terminating in inwardly-extending bills 12, that engage over the base-flange of the rail, as clearly shown in Fig. 2. The inwardly-extending bills are provided with sockets 13, these sockets receiving the outer tapered ends of freely-swinging cam

elements 14. The said cam elements, as disclosed in Fig. 4, have pivoted bearings in the sockets, and their inner opposing ends are provided with curved surfaces 15, that are disposed eccentrically to the axes of movement of the elements. The curved surfaces are arranged to bear against the opposite faces of the rail-web.

The jaws 10 are connected by spaced devices. One of these devices is in the form of a plate 16, located transversely beneath the anchor-block and having longitudinally-disposed slots 17. The lower ends of the jaws have reduced portions 18, which pass through the slots, said jaws terminating at their lower end in transversely-disposed heads 19. The heads 19 are of less width and less length than the slots 17 and are located transversely of the same when the parts are in their normal relation. This, it is believed, will be apparent by reference to Fig. 5. It will also be clear that when the jaws are turned sidewise the heads can freely pass through the slots, and when placed in position upon opposite sides of the anchor-block, being disposed transversely of said slots, the parts will be securely interlocked. The intermediate portions of the jaws are connected by a tie-bolt 20, preferably angular in cross-section, this tie-bolt extending beneath the rail and being seated in a recess 21, formed in the anchor-block. The said tie-bolt passes through openings made in the enlarged portions 11 of the jaws, one end of the bolt having a suitable head 22, the other end having a nut 23 threaded thereon, which constitutes an adjustable clamp for drawing the jaws toward each other.

It will be apparent that when the structure is in position on a rail it will be securely anchored in the ballast, as said anchor-block is not only in said ballast, but abuts against the adjacent ties. The jaws 10 are likewise embedded, and, furthermore, because of the tie-bolt 20 engaging in the slot 21 of the anchor-block said jaws cannot slip along the block. The freely-swinging cam elements will bind strongly against the rail-web, and in case said web starts to move in either direction the elements will swing upon their pivot-axes, causing the cam or eccentric surfaces to move toward each other, and thus more securely bind upon the rail. By this structure rails can be fastened securely against creeping or longitudinal movement.

in either direction. The apparatus is simple and is made up of parts not liable to breakage or derangement.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described my invention, what I claim as new, and desire to secure by Letters Patent, is—

1. In a device of the character described, the combination with anchoring means, including an upstanding device having a socket in its inner end, of a freely-swinging cam element having its outer end pivotally mounted in the socket and having a rail-engaging surface that is disposed eccentrically to the axis of movement of said element.

2. In a device of the character described, the combination with anchoring means including a clamping-jaw, of a cam element having a pivoted bearing on the jaw and an edge that is disposed eccentrically to the bearing and is arranged to engage a rail.

3. In a device of the character described, the combination with anchoring means including a clamping-jaw having an overhanging rail-engaging bill, said bill being provided with a socket, of a tapering cam element having one end fitted in the socket and its opposite end provided with a cam-surface arranged to bear against the rail-web.

4. In a device of the character described, the combination with rail-embracing jaws, of freely-swinging cam elements mounted on the jaws and having rail-engaging surfaces disposed eccentrically to the axes of movement of said elements, the opposing ends of said surfaces thus moving toward each other upon the swinging movement of the elements in either direction.

5. In a device of the character described, the combination with rail-embracing jaws having inwardly-extending bills provided with sockets, of freely-swinging cam elements having their outer ends pivotally mounted in the sockets and having eccentrically-disposed inner surfaces arranged to engage the opposite sides of a rail-web.

6. In a device of the character described, the combination with rail-embracing jaws having depending portions arranged to extend below the rail, of rail-engaging means carried by the jaws, and spaced upper and lower devices separately connecting the depending portions of the jaws and arranged to extend beneath the rail.

7. In a device of the character described, the combination with rail-embracing jaws, of rail-engaging means mounted movably thereon, and spaced devices separately connecting the jaws, one of said devices being adjustable to draw the jaws toward each other.

8. In a device of the character described, the combination with rail-embracing jaws, of rail-engaging means movably mounted on the upper ends of the jaws, a device connecting the lower ends of the jaws, and a tie-bolt connecting intermediate portion of the jaws.

9. In a device of the character described, the combination with rail-embracing jaws, of rail-engaging means carried by the upper ends of the jaws, a device connecting intermediate portions of the jaws, and a connecting-plate having openings at its ends, said jaws having heads at their lower ends that pass through the openings and interlock with the connecting-plate.

10. In a device of the character described, the combination with an anchor-block arranged to be placed between two ties, of rail-embracing jaws located on opposite sides of the block and having sockets in the inner sides of their upper end, cam elements pivotally mounted in the sockets and arranged to engage the opposite sides of a rail-web, a tie-bolt connecting the jaws below the sockets, a connecting-plate extending beneath the anchor-block and having longitudinally-disposed slots, and transversely-disposed heads carried by the lower ends of the jaws, said lower ends passing through the slots with the heads located transversely beneath the same.

In testimony that I claim the foregoing as my own I have hereto affixed my signature in the presence of two witnesses.

JAMES G. BARRETT.
